UNITED STATES PATENT OFFICE

2,102,236

DRILLING IMPLEMENT

Harry C. Johansen, Michigan City, Ind., assignor
to Sullivan Machinery Company, a corporation
of Massachusetts

Application May 4, 1934, Serial No. 723,919

4 Claims. (Cl. 255—61)

This invention relates to drilling implements and more particularly to improvements in a drilling implement of the type adapted to use with rotary drilling apparatus.

5 An object of this invention is to provide an improved drilling implement. Another object is to provide an improved drilling implement adapted to use with a rotary drilling apparatus. A further object is to provide an improved drilling 10 implement of the so-called "chatter" bit type having improved means for imparting a "chattering" or vibrating action to the cutting edges during the drilling operation thereby to improve the drilling action of the drilling implement. Yet 15 another object is to provide an improved torsion spring type "chatter" bit having associated therewith improved rotation limiting means between relatively rotatable parts of the bit whereby when the bit sticks breakage of the torsion 20 spring is prevented. These and other objects 25 will, however, hereinafter more fully appear.

In the accompanying drawing there is shown for purposes of illustration one form which the invention may assume in practice.

25 In this drawing,—

Fig. 1 is a sectional view through a drill rotation and feeding mechanism with which the illustrative embodiment of the improved drilling implement is associated.

30 Fig. 2 is a view partially in longitudinal section and partially in elevation through the illustrative form of the improved drilling implement.

Fig. 3 is a cross sectional view taken on line 35 3—3 of Fig. 2.

Fig. 4 is a side elevational view of the drill bit.

Fig. 5 is an end view of the cutter bit.

In this illustrative embodiment of the invention the improved drilling implement generally 40 designated 1 is associated with a "strip borer" drill having feeding and rotation mechanism, although it will be evident that the improved drilling implement may be used with rotary drilling apparatus of various other types.

45 The drill rotation and feeding mechanism shown comprises a rotation member 2 journaled within the drill head frame 3. The rotation member 2 is provided with an axial drive opening 4 of polygonal cross section through which is 50 slidable an axially movable and rotatable drive rod 5 likewise of polygonal cross section for loosely fitting the polygonal drive opening in the rotation member. This drive rod carries a chuck 6 of any suitable design for connecting the feed 55 stem 7, extending axially through the drive rod,

to the drive rod for axial and rotatable movement therewith. The drive rod and stem may be fed axially as they are rotated by a hydraulic feed mechanism comprising parallel feed cylinders 8, 8 mounted on the drill head frame and 5 having reciprocable therein feed pistons 9, 9. The rods of these feed pistons are connected to a cross frame 10 carrying a thrust bearing head 11 in which the drive rod 5 is journaled. It will thus be seen that as the drill rod and feed stem 10 are rotated by the rotation member, they may be fed axially relative thereto by the feed piston. Liquid under pressure may be supplied to the feed cylinders through any suitable connections and the feeding pressure may be regulated by 15 any suitable control means.

The drilling implement 1 is connected to the feed stem 7 and generally comprises a drill bit 12 connected to the stem through a "chattering" or vibration producing connection 13 so that 20 when the bit is rotated by the drive rod 5 the cutting portions thereof have imparted thereto a "chattering" or vibrative chipping action. In this instance the feed stem 7 is threadedly connected at 14 to a bushing 15 in turn threadedly 25 connected at 16 to a tubular outer casing or spring housing 17. Secured as by welding or otherwise to the outer end of this tubular casing 17 as at 18 is a drive bushing 19 having an axial bore 20. In accordance with this invention, arranged within the tubular casing 17 is the improved bit "chattering" or vibrating means comprising a coiled torsion spring 21 secured at its upper end as by welding or otherwise to a cylindrical portion 22 of an upper spring end plate 30 35 23. This member 23 is connected, as by clutch teeth 24, to the lower end of the bushing 15. The lower end of this spring is similarly secured to a cylindrical portion 25 of a lower spring end plate 26 in turn similarly connected as by clutch 40 teeth 27 to the head 28 of a rod-like drive plug 29. This drive plug is guided in the tubular housing for axial and rotative movements relative thereto and extends outwardly through the bore 20 in the drive bushing 19 and is threadedly 45 connected at 30 at its lower end to a bit head 31. The body of the bit 12 is mounted in a transverse slot 32 in this bit head and is secured therein by a holding bolt 33. The coiled torsion spring 21 is a very powerful spring and adapted to resist torsional strain in such a manner that when it yields it stores up a very powerful force which acts in a direction to rotate the drive plug 29 forwardly through an arc equal to that through which it has been twisted. 50 55

- Improved means is provided for limiting the rotative movement of the drive bushing 19 with respect to the drive plug 29 so that when the drill bit 12 sticks or is unduly resisted, breakage of the coil "chatter" spring 21 is prevented, and herein comprises lateral lugs 34, 34 formed on the drive plug 29 and movable in arcuate slots 35, 35 in the drive bushing and engageable with lugs 36, 36 on the drive bushing. The slots 35 are longitudinally elongated so when the drive plug has axial movement relative to the drive plug 19, the lugs 34 may move longitudinally in the slots. It will thus be seen that when the drive plug 29 is held against rotative movement by the sticking of the drill bit 12 the torsion spring 21 will yield until the lugs 36 on the drive bushing 19 engage the lugs 34 on the drive plug 29, so upon further rotative movement of the drive bushing the drive between the parts is positive.
- The body of the drill bit 12 is centrally slotted at 37 to provide relatively long blades 38 having cutting edges 39, and these blades are so formed as to have a certain amount of inherent resiliency so as to cooperate with the torsion "chatter" spring 21 in the vibrating of the bit cutting edges. In other words, the cutting blades of this bit are so formed so that when the bit is rapidly rotated, and, due to their inherent flexibility and the substantial degree of vibration which is effected as a result of the feeding pressure to which the bit is subjected will undergo a "chattering" or vibrating effect which cooperates with the torsion "chatter" spring in the vibrating of the bit cutting edges.
- The operation of the improved drilling implement will be clearly apparent from the description given. During the drilling operation the drilling implement is rotated by the rotation means and a relatively powerful feeding force is imparted to the drilling implement by the hydraulic feeding mechanism. As the drilling implement is rotated, the cutting edges 39 will cut away the rock with an action which, due to the presence of the torsion "chatter" spring 21, will involve a phenomenon or characteristic not found in a drill bit of the usual rotary type. The presence of the torsion "chatter" spring will permit very brief lags in the rotative speed of the bit compared with the rotative speed of the drive rod, and the inherent resiliency in the cutting blades will cooperate with the torsion spring to increase the duration of these lags. As soon, however, as a sufficient pressure or rotative force builds up to break away the rock which has been obstructing the rotative movement of the bit, the torsion spring will restore the bit with a shocking, "chattering" action to substantially the same position it occupied with respect to the drive rod prior to the occurrence of the lag. This operation will be effected many times a minute, and due to the friable or brittle nature of the rock, for the drilling of which this drilling implement is particularly adapted, will result in a much more rapid removal of the rock, the rock being not merely planed off with a drilling action, but removed in chips of substantial size. The improved rotation limiting means associated with the "chattering" means prevents the torsion spring from being broken or twisted off when the drill bit sticks. These and other uses and advantages of the improved drilling implement will be clearly apparent to those skilled in the art.

While there is in this application specifically

described one form which the invention may assume in practice, it will be understood that this form of the same is shown for purposes of illustration and that the invention may be modified and embodied in various other forms without departing from its spirit or the scope of the appended claims.

What I claim is new and desire to secure by Letters Patent is:

1. In a rotary drilling implement, a rotary driving member, a relatively rotatable member carrying a drill bit, a hollow longitudinal element disposed between said driving member and said bit carrying member, a torsion spring connecting said bit carrying member to said driving member and enclosed within said longitudinal element, said bit carrying member rotatable relative to said longitudinal element upon yielding of said spring while remaining in the same relative longitudinal relation with said element, and abutment means associated with said longitudinal element and comprising an abutment on said bit carrying member and a cooperating abutment on said longitudinal element for limiting yielding of said torsion spring, due to relative rotation between said members, upon sticking of said drill bit.

2. In a rotary drilling implement, a rotary driving member, a relatively rotatable connector element, a torsion spring connecting said connector element to said driving member, a sleeve surrounding said spring, said sleeve rigidly connected to said driving member, a drill bit secured to said connector element, said drill bit and connector element being reciprocable rectilinearly and without rotation relative to said sleeve on compression and extension of said spring, and abutment means comprising an abutment on said connector element engageable with an abutment carried by said sleeve for limiting yielding of said spring, upon relative rotation between said connector element and sleeve, when the drill bit sticks.

3. In an implement of the character described, a drive element, a drilling element, said elements being relatively rotatable, cylindrical guide portions fixed relative to said elements and axially aligned, a sleeve secured to one of said guide portions and slidably cooperating with the other, means fixed relative to said last mentioned portion for limiting movement of the latter into said sleeve, a torsion spring connecting said elements, and abutment means comprising an abutment fixed as regards rotation relative to said drilling element and a cooperating abutment fixed as regards rotation relative to said drive element for limiting relative rotation between said elements providing substantially the same limit irrespective of the degree of longitudinal deformation of the spring.

4. In an implement of the character described, a rotary drive element, a drilling element, said elements being relatively rotatable, yielding means connecting said elements, and means comprising an abutment fixed as regards rotation relative to said drilling element and a cooperating abutment fixed as regards rotation relative to said drive element for limiting yielding of said yieldable means, upon relative rotation between said elements, providing substantially equal limits of yield irrespective of the axial deformations of said yielding means.

HARRY C. JOHANSEN.
